Primary Examiner — Cynthia M. Chin(74) *Attorney, Agent, or Firm* — Optimus Patents US.
LLC(57) **CLAIM**

The ornamental design for a floating platform, as shown and described.

DESCRIPTION

FIG. 1 is a top perspective view of a platform for yachts;
 FIG. 2 is a bottom perspective view thereof;
 FIG. 3 is a left and right side view thereof;
 FIG. 4 is a front and rear view thereof;
 FIG. 5 is top view thereof; and,
 FIG. 6 is a bottom view thereof.

Shading lines are for illustrative purposes only and form no part of the claimed design.

The shading lines shown in the drawing represent the three-dimensional contour of the claimed design, and are not intended to indicate surface decoration.
